UNITED STATES PATENT OFFICE.

JOSEPH MORRIS, OF ELTON, NEAR CHESTER, ENGLAND.

SHELL OR PROJECTILE.

1,345,689.

Specification of Letters Patent.

Patented July 6, 1920.

Application filed April 18, 1918. Serial No. 229,359.

To all whom it may concern:

Be it known that I, JOSEPH MORRIS, subject of the King of Great Britain, residing at Elton, near Chester, in the county of 5 Chester and Kingdom of England, have invented certain new and useful Improvements in Shells or Projectiles, of which the following is a specification.

This invention has reference to shells or 10 projectiles of the kind wherein one or more rifling bands of compressed paper or other like relatively soft material, are held in place between the body of the shell and a clamping ring or head, the function of such 15 rifling bands being to take into the spiral grooves in the rifled bore of the gun, and at the same time serve as a gas check.

The present invention has for its object 20 to provide certain improvements in this kind of shell or projectile, by which the bands are held more securely in position and any turning of the bands independently of the shell body is prevented.

The invention is characterized by the fact 25 that the abutting faces of the band and shell body are provided with notches so that the projections on one part enter the notches in the other part, or in that the shank of the clamping ring or head is provided with 30 a neck portion notched longitudinally and the inside of the band or bands with fins or splines which are adapted to enter the notches so as to become interlocked with the clamping head or ring.

35 The invention will be understood from the following description, reference being had to the accompanying drawings, in which:—

Figure 1 is a side elevation of a shell 40 partly in section with my invention applied thereto,

Fig. 2 a face view of the soft rifling band showing the notches together with clamping head with its shank and notched neck, and 45

Fig. 3 a sectional elevation showing another form of the invention.

In these figures, A is the annular band of compressed paper, cardboard, papier mâché or the like which is affixed to the end of the 50 projectile B opposite to that of the conoidal point. This affixing is effected according to the present invention by means of a clamping ring or head C the shank C¹ of which enters the bore of the projectile. The 55 clamping head has a neck C² to receive the band A, the said neck being notched longi-

tudinally at D at intervals all around its circumference, and the inside of the annular band A has formed integrally with it, fins or splines A¹ which are adapted to 60 enter the notches D. The annular band A is slipped longitudinally onto the neck C² so that the splines A¹ take into the notches D in the neck C² of the shank C, and becomes interlocked therewith. The shank 65 C¹ of the pin which may be screw threaded, is now screwed into corresponding threads in the bore of the projectile B and the annular band A becomes tightly clamped and compressed between the projectile B 70 and the head C, the shank C¹ being locked in position by the set pins E. The annular band cannot rotate independently of the shank so that any rotary motion imparted to the annular band A will be imparted to 75 the projectile also, because of the interlocking of the band A with the head C and the projectile B. The neck C² may be made slightly shorter than the width of the annular band so as to insure a tight compression 80 of the latter when the head is screwed up. The annular band is shown as in Fig. 1 being made in one piece but it can if desired be built up of a plurality of layers of paper cardboard or the like as shown in Fig. 3. 85

If the annular band be made slightly larger than the outside diameter of the projectile and the bore of the gun, it will on the explosion of the charge, become forced into the shallow spiral grooves or rifling with 90 which the gun is provided, and which thus spin the projectiles and insure a complete centering thereof. Moreover it gives great accuracy in firing and avoids the disadvantage which results from the use of lead 95 covered projectiles namely the special strains imposed on the gun and the necessity of using lubrication. The abutting faces of the band and the bottom of the projectile may be serrated or grooved or be otherwise 100 formed so that projections on one part enter depressions in the other and thus further insure their interlocking together and prevent the band turning or twisting independently of the projectile. 105

I declare that what I claim is:—

1. In an explosive projectile, the combination with the projectile body having an interior bore and an opening to the said bore at the rear of the projectile, of a 110 clamping head having a shank which enters the bore of the body and closes the opening,

a neck integral with and located between the shank and the head, longitudinal notches in the neck all around its circumference at intervals, and at least one annular rifling band of relatively soft material located directly between the head and the rear of the projectile body and filling the space between the same, the said band having fins formed integrally therewith and adapted to enter the notches in the neck.

2. In an explosive projectile, the combination with the projectile body having an interior bore and an opening to the said bore at the rear of the projectile, of a clamping band having a shank which enters the bore of the body so as to close the opening, a neck integral with and located between the shank and the head, serrations on the rear face of the projectile body, and annular rifling bands of relatively soft material located between the head and the projectile body, the face of the band next the rear face of the projectile having serrations which engage the serrations at the rear face of the projectile body.

3. In an explosive projectile, the combination with the projectile body having an interior bore and an opening to the said bore at the rear of the projectile, of a clamping head having a shank which enters the bore of the body so as to close the opening, a neck integral with and located between the shank and the head, longitudinal notches in the neck, annular rifling bands

of relatively soft material located between the clamping head and the projectile body and filling the space between the same, such bands having projections which enter the notches in the neck, and a set pin for locking the shank in the projectile body with the bands in a compressed condition.

4. In an explosive projectile, the combination with the projectile body having an interior bore and an opening to the said bore at the rear of the projectile, of a clamping head having a shank which enters the bore of the body so as to close the opening, a neck integral with and located between the shank and the head and filling the space between the same, longitudinal notches in the neck, rifling bands of soft material located between the clamping head and the projectile body, such bands having projections which enter the notches in the neck, and means for holding the head with the bands in tight compression between it and the rear end of the projectile, the said neck portion being made rather shorter than the width of the rifling bands so as to allow for a tight compression being obtained.

In witness whereof, I have hereunto signed my name this 18th day of March, 1918, in the presence of two subscribing witnesses.

JOSEPH MORRIS.
